UNITED STATES PATENT OFFICE.

LEONARD G. QUACKENBOSS, OF CHICAGO, ILLINOIS.

SUPPORTING-FRAME.

SPECIFICATION forming part of Letters Patent No. 591,934, dated October 19, 1897.

Application filed October 31, 1896. Serial No. 610,708. (No model.)

To all whom it may concern:

Be it known that I, LEONARD G. QUACKENBOSS, a citizen of the United States, residing at Chicago, in the county of Cook and State 5 of Illinois, have invented a certain new and useful Improvement in Supporting-Frames, (Case No. 6,) of which the following is a full, clear, concise, and exact description, reference being had to the accompanying drawings, 10 forming a part of this specification.

My invention relates to supporting-frames, and is particularly applicable for the support of window-boxes, such as are commonly in use to contain flowers or plants. It is desirable 15 that such a box should not be stationary, either upon the inside or outside of the window-frame, but should be movable to and fro. My invention accomplishes such a result without obstructing the movement of the 20 window-sash, whether the box be upon the outside or inside, and may be generally described as consisting of a frame to which the box is secured, said frame having suitable tracks or runways which may be thrown like 25 a bridge across the opening from either position of the box. The box may be then moved across, traveling upon said runways, when, the box having reached the end of its travel, the runways may be turned out of the way to 30 allow the window-sash to be moved.

I will describe my invention as applied to a window-box, but it is evident that its use is not limited to such application.

The details of my invention may be more 35 readily understood by reference to the accompanying drawings, in which—

Figure 1 is a plan view of a window-box and its supporting-frame constructed in accordance with my invention. Fig. 2 is a side elevation thereof, the window-frame having been removed on one side for clearness, and different positions of the parts being indicated in dotted lines. Fig. 3 is a detail view of a socket in which a lug on one of the runways 40 is adapted to be retained. Fig. 4 is a detail sectional view taken on line 4 4 of Fig. 2. Figs. 5 and 6 are detail views showing in cross-section the runways which are thrown across the space to be traversed by the box. Fig. 7

is a detail sectional view taken on line 7 7 of 50 Fig. 2.

Like letters refer to like parts throughout the different views.

The box *a* is provided at each end with a metallic slotted runway *b* at the top, and a 55 similar runway *b'* at the bottom, the runways being secured to a metallic plate *a'*, which is fastened to the box by screws. A complementary runway *c* is provided, having lugs *c'* *c''*, which may be supported in metallic sockets *d* *d'*, respectively, mounted on each side of the window-frame.

A roller *e* (shown in Fig. 7) is provided with shoulders *e'* *e''*, which engage the slots in runways *c* and *b*, respectively, constituting a bearing or connection between them and permitting relative longitudinal movement only, except when the runway *b* has come to the end of its travel along complementary runway *c*, which latter may then be turned about the 70 lug *c'* and roller *e* as a pivot into the position shown in dotted lines in the right-hand portion of Fig. 2, the lug *c'* being raised out of the socket *d*, where it normally rests.

A rib *c*³ extends the length of the complementary runway *c* on one side, engaging the under side of runway *b* when the box is being moved, and supporting it. The rib *c*³ also prevents the complementary runway *c* from turning about roller *e* as a pivot until the box 75 has reached one end or the other of its travel.

A runway *f*, complementary to runway *b'*, is provided, similar to complementary runway *c* except that its rib *f*³ extends some distance beyond the end of the runway proper, in order to better support the box. The rib *f*³ is 85 also somewhat wider than rib *c*³, and its outer edge is turned up to form a guide *f*⁴.

Lugs *f'* *f''* on complementary runway *f* normally rest in sockets *g* *g'*, secured to the window-frame. Arms *g*² *g*³, pivoted at *g*⁴ *g*⁵, respectively, hang over the sockets *g* *g'* and serve as locking devices to retain the lugs *f'* *f''* within their sockets.

The roller *h* (shown in Fig. 4) is similar in 95 all respects to roller *e*, the shoulders *h'* *h''* engaging the slots of runways *b'* and *f*, respectively, and serving as a bearing and connec-

tion between said runways and permitting their relative longitudinal movement. A brace l is pivoted at l' to the box a , the end l'' thereof abutting against the complementary runway f and sustaining the box against sagging.

When the box is in the position shown in full lines in Figs. 1 and 2, the lugs c' and c'' of complementary runway c resting in their sockets $d' d''$, and the lugs f' and f'' of complementary runway f resting in sockets $g' g''$, the window-sash cannot be lowered, its path being obstructed by said runways; but should it be desired to lower the window-sash, the upper complementary runway c is turned about lug c'' and roller e as a pivot, into the position shown in dotted lines, a slot c^4 in the rib c^3 engaging with a lug b^2 , provided upon runway b . Lower complementary runway f may now be turned about lug f'' and roller h as a pivot, lug f' having been released from engagement with socket g . The end of rib f^3 during the first few degrees of rotation is supported by a lug k , mounted upon the lower runway b' . The brace l meanwhile drops into a vertical position, as indicated in dotted lines. The box is now supported by lugs $c^2 c^2$, resting in sockets $d' d''$, and lugs $f^2 f^2$, resting in sockets $g' g''$, and the movement of the window-sash is unobstructed. When it is desired to bring the box over to the other side of the window-frame, the complementary runways c and f are returned to their normal positions and the box may be slid back along said runways to the position shown in dotted lines on the left in Fig. 2, bearing on rollers $e e$ and $h h$ and being supported by the extensions or ribs $f^3 f^3$ of complementary runways $f f$. The ends l'' of braces l slide over the tops of runways f and drop at the end into the position shown. In this position of the box the complementary runways c may be turned back about lugs c' and rollers e as pivots, and complementary runways f may be turned about lugs f' and rollers h as pivots out of the path of the window-sash, the box now being supported by lugs $c' c'$, resting in sockets $d' d''$, and lugs $f' f''$, resting in sockets $g' g''$.

As the use of my invention is not restricted to its application to a window-box, I shall use the term "box" in the claims as meaning any object which it is desired to support in the adjustable manner of my invention.

Having thus described my invention, what I claim as new, and desire to secure by Letters Patent, is—

1. The combination with a window-casing of a box, runways provided in said casing, adapted to span the space to be traversed by the box on which the box may travel, and a mounting for said runways which permits the

removal thereof from the space traversed by the box after the box has reached either end of its travel, substantially as described.

2. In a supporting-frame, the combination with runways associated with the box, of complementary runways normally spanning the space to be traversed by said box, a sliding or rolling connection between each of said runways and its complementary runway, and pivotal supports, one at each end of said complementary runways, whereby each of said complementary runways may be rotated about one of its supports as a pivot, when the box has reached the end of its travel, to remove said complementary runways from obstructing said space, substantially as described.

3. In a support for window-boxes, the combination with the box-body, of runways associated therewith, complementary runways normally spanning the window-frame, a roller connection between each of said runways and its complementary runway, whereby the box may be moved to and fro across the window-frame, and pivotal supports, one at each end of each of said complementary runways whereby the latter may be rotated out of the path of the window-sash, when the box has reached either end of its travel, substantially as described.

4. In a supporting-frame for a window-box, the combination with the box-body, of runways adapted to span the space to be traversed by the box, on which runways the box may travel, a sliding connection between the box and each of said runways, and pivotal supports at each end of said runways about one of which supports said runways may be rotated out of the path of the window-sash when the box has reached the end of its travel, substantially as described.

5. In a support for a window-box, the combination with the box-body, of slotted runways associated therewith, complementary slotted runways adapted to be thrown across the space to be traversed by the box, lugs upon each end of said complementary runways, sockets upon the window-frame adapted to receive and support said lugs, and rollers provided each with two shoulders, one of said shoulders adapted to engage the slot in one of said runways, and the other of said shoulders engaging a corresponding slot in one of said complementary runways, substantially as described.

In witness whereof I hereunto subscribe my name this 27th day of October, A. D. 1896.

LEONARD G. QUACKENBOSS.
